UNITED STATES PATENT OFFICE.

CHARLES H. EMERSON, OF YONKERS, NEW YORK.

TOBOGGAN.

SPECIFICATION forming part of Letters Patent No. 366,083, dated July 5, 1887.

Application filed September 28, 1886. Serial No. 214,722. (No model.)

To all whom it may concern:

Be it known that I, CHARLES H. EMERSON, of Yonkers, in the county of Westchester and State of New York, have invented certain 5 new and useful Improvements in Toboggans; and I do hereby declare that the following specification, taken in connection with the drawings furnished and forming a part of the same, is a clear, true, and complete description 10 of my invention.

My said improvements relate to that variety of toboggans in which the side slats are bent and carried up to form the hood in such a manner as to retire the outer edges of said 15 slats at the hood from contact with the sides of a slide; and the object of my invention is to afford special strength to the hood for enabling it to resist injury from a square abutment against obstacles, and also provide 20 against cornerwise thrusts, and I attain these ends by, for the first time, crossing the bent ends of the side slats one upon the other at the hood.

In its best form, a hood embodying my invention has the front bent ends of the side slats bent inward and crossed within the hood and beneath the bent ends of the intermediate slats which form the hood; but fairly good results will accrue if said bent ends are crossed 30 upon each other on the outer surface of the hood.

Referring to the drawings, Figure 1 is a side view of one form of toboggan embodying my invention. Fig. 2 is a top view of the same. Fig. 3 is a sectional view thereof on line $\alpha\alpha$, Fig. 2. Figs. 4 and 5 are lateral sections, respectively, on lines yy and zz , Fig. 2. Fig. 6 is a front view of a toboggan having its side slats extended upwardly and across 40 each other in front of the curved or bent head. Fig. 7 is a side view of the toboggan shown in Fig. 6. Fig. 8 is a side view of a toboggan having side bars and my readily-detachable straining-links.

In each of the figures the inner bearing-slats, a , are as heretofore, and it is to be understood that their bearing-surfaces may be variously formed, and that they may be of various thicknesses without in any manner affecting my invention.

In such of the figures as show the front lat-

eral cross-bar, b , it is to be understood that it is bent or curved at least on its lower surface, so that the slats when secured thereto will present a laterally-convex bearing-surface, as 55 clearly indicated. The lateral cross-bars b' and b'' , and sometimes b^3 , are also bent or curved, but to a lesser degree than the cross-bar b , so that the bearing-surface of the toboggan will merge from a convex to a flat surface, 60 preferably in front of the middle portion of the toboggan.

It must be understood that I do not preclude myself from making the entire bearing-surface laterally convex, as in some cases that 65 construction is deemed desirable. In some cases the convex bearing-surface is developed wholly by laterally curving the outer slats, c , the inner slats, a , affording a substantially flat lateral bearing-surface, as heretofore. In Figs. 70 1, 2, and 3 the front ends of said slats c are shown to be extended inwardly within the head, and then crossed and secured to the head or hood A by means of a suitable pin or screw, and preferably having an intermediate bar, d , 75 and the slats a are curved or bent upwardly and rearwardly to form the head, and they are firmly bound together by means of the head-bar e and suitable pins, rivets, or screws.

In Fig. 1 the straining-links f are secured at 80 one end to the head-bar e , preferably by means of a hook and a thin plate of metal attached to said bar, having holes to receive said hooks. These links f are attached to the cross-bar b , preferably by means of a hook or an eyebolt, 85 and they are constructed in two parts, one of which is screw-threaded, so that the two parts can be coupled together by a turn-buckle, f' , in a manner well known, thus providing for adjustability in the matter of straining the head, 90 as well as for convenient detachability.

In Figs. 6 and 7 the side slats, c , as before described, are turned up laterally at the edges; but instead of passing upward and inward within the head they cross each other outside 95 of the head and are firmly secured to the head-bar e ; but the straining-link f is as before described.

In Fig. 8 the side slats, c , are shown as in Fig. 1; but in this form of toboggan there are 100 side rails or bars, g , on top of the several cross-bars at their ends and firmly secured

thereto. The front end, g' , of said side rail extends forward of the cross-bar b , and its outer end serves as a means for coupling with the straining-link f , which in this case is not 5 adjustable, but is readily detachable, because it has a loop or eye at its lower end which is occupied by the front end, g' , of the side bar, g . By thus crossing the bent ends of the side slats at the hood upon each other, and securing them as indicated, the hood is greatly strengthened and well adapted to successfully resist injuries during such full-front collisions as are liable to occur at the foot of a slide, as well as during cornerwise thrusts, which fre-

quently occur, especially against the side walls 15 of a slide.

Having thus described my invention, I claim as new and desire to secure by Letters Patent—

In a toboggan, the combination, with the hood, of the side slats, upwardly bent at their 20 front ends, inclined inward, and crossing each other at the hood and united thereto, substantially as described.

CHARLES H. EMERSON.
